EYELETING-MACHINE.

1,303,194.

Specification of Letters Patent.

Patented May 6, 1919.

Application filed March 3, 1917. Serial No. 152,421.

To all whom it may concern:

Be it known that I, PERLEY R. GLASS, a citizen of the United States, residing at Brookline, in the county of Norfolk and 5 State of Massachusetts, have invented certain Improvements in Eyeletting-Machines, of which the following description, in connection with the accompanying drawings, is a specification, like reference characters on 10 the drawings indicating like parts in the several figures.

This invention relates to improvements in machines for inserting fasteners. While it is herein shown as embodied in a machine 15 for inserting eyelets in the uppers of boots and shoes it will be understood that many of its features are not limited in their application to this or any other particular form of machine.

20 It is important for purposes of speed and precision that the eyelet to be set should be positioned for delivery by the raceway accurately in alinement with the eyelet setting device and that when presented for delivery 25 the eyelet should be so held that the setting device may engage and draw it from the raceway without retardation or displacement which would in any way subject the setting device to strain. This is particularly true 30 in machines embodying an expandible setting member such, for example, as that shown in Letters Patent of the United States No. 1,271,720, granted July 9, 1918, upon the application of H. W. Kenway, for in 35 such a machine if the upsetting die encounters the eyelet flange instead of passing freely through the eyelet barrel a section of the upsetting die is liable to be broken.

With a view to improving the operation 40 of fastener inserting machines an important feature of the invention consists in means for positively positioning the endmost fastener in the raceway preliminarily to its delivery to the setting device. As herein 45 shown in an eyeletting machine this result is secured by providing a spindle which assumes positive control of the second eyelet of the series while said eyelet is in the raceway and during the cycle of the machine 50 next prior to the delivery of the first eyelet, the spindle being arranged to enter and hold the second eyelet while the eyelet and raceway are relatively moved to feed the eyelet positively to a more advanced position in the 55 raceway. Such construction permits the use

of a spindle sufficiently strong and best shaped for the function of positioning the eyelet without reference to other limiting considerations and effects such positive treatment of the eyelet as to insure uniform results. 60

Another feature of the invention consists in a raceway provided at its end with a movable jaw or latch for holding and positioning the endmost fastener and so constructed and arranged that it may be moved to release the endmost eyelet and leave it free at the time of its delivery. An advantage of such a construction is that after an eyelet or other fastener has been moved to 70 the point of delivery to the setting device it is released so that no strain whatever is imparted to the setting device in the delivery operation. As herein shown the retaining latch is so positioned and shaped that the 75 movement of another eyelet in the raceway serves to disengage the latch from the endmost eyelet, in this case such other eyelet being positively moved by the positioning spindle above discussed. 80

A difficulty heretofore encountered in eyeletting machines has been that, by reason of long use and wear or faulty adjustment, the movable raceways have at times developed a side play which has permitted inaccuracy 85 in locating the eyelet to be delivered to the inserting die. With a view to obviating this defect, another feature of the invention consists in a raceway supported upon links having a positive guiding connection with the 90 machine frame at a point adjacent to the end of the raceway. In the illustrated embodiment of the invention the raceway is provided with a projecting tongue arranged to slide in a guideway formed in the machine 95 frame beneath the raceway and adjacent to its delivery end. By such construction the path of movement of the raceway is accurately and positively controlled and the possibility of side play eliminated. 100

It sometimes happens that the barrel of an eyelet is more or less obstructed by a fin of enamel or a chip of eyelet metal which has not been entirely removed in manufacturing the eyelet. This is detrimental to rapid and accurate handling of the eyelet for obvious reasons and in accordance with another feature of the invention it is proposed to clear the eyelet of any such obstruction before it is presented to the setting devices. 110

As herein shown this operation is effected by the spindle which is provided for positioning the eyelet in the raceway but it is within the scope of the invention to provide separate or different means for performing this operation if so desired.

These and other features of the invention will be best understood and appreciated from the following description of a preferred embodiment thereof selected for purposes of illustration and shown in the accompanying drawings, in which—

Fig. 1 is a view in perspective of so much of an eyeleting machine as is necessary to understand the present invention;

Figs. 2 and 3 are detail views in perspective;

Figs. 4, 5, 6 and 7 are views in side elevation illustrating the successive steps in the cycle of the machine;

Fig. 8 is a sectional view through the lower setting device;

Fig. 9 is a sectional view on an enlarged scale showing the setting devices in position at the conclusion of the setting operation, and

Fig. 10 is a plan view of the end of the raceway.

The machine frame 2 is provided with vertical bearings for a plunger 4 carrying the setting devices. The plunger 4 is reciprocated vertically by a cam track cut in the rear face of the cam disk 54 upon the shaft 52. The frame also supports a stationary work plate 70 above which operate a punch lever 80 and a feeding lever 34 which will be referred to hereinafter.

The lower setting die 10 is shaped at its upper end to fit the flange of the eyelet to be set and is adjustably mounted in the upper end of the plunger 4, being shouldered to rest upon a hollow bolt 6 threaded into the plunger and provided with a lock nut 8. The setting die 10 is bored to receive the

upsetting die member, the setting surface of which is formed by the lower surface of an overhanging shoulder made up of expandible sections 12. The body of the upsetting die 14 is hollow to receive the stem of the

die-expanding member 24 and at its lower end is threaded into a movable angle piece 16. The angle piece 16 is guided for movement in the machine frame and projects in through a slot 5 in the wall of the plunger as shown in Fig. 8. Beneath the overhanging end of the angle piece 16 is disposed a hollow flanged core 18 between which and the bottom of the plunger 4 is interposed a stiff compression spring 20 tending at all

times to elevate the angle piece 16 and the upsetting die 12 carried thereby. The stem 26 of the die-expanding member 24 is provided at its lower end with a head 28 against which bears the upper end of a compression spring 30 contained within a hollow core 18

and tending to elevate the die-expanding member. It will be understood that the eyelet to be set is delivered to the setting die 10 and the clenching operation is effected by relative movement of the die 10 and the upsetting die 12 during which the spring 20 is compressed. The novel features of this form of expanding set and the associated parts have not been claimed herein since they form the subject-matter of a co-pending application of Ralph F. Knight, Serial No. 179,243, filed July 7, 1917.

Eyelets are supplied to the setting die 10 in line with the member 12 by a raceway 72 supported in part by a link 71 and pivots of 80 which one is indicated at 73 in Fig. 1. The axes of these pivots are at right angles to a vertical plane extending from front to rear as is customary in machines of this type. The raceway is provided upon its lower side 85 with a downwardly projecting tongue 74 which projects into a groove 75 formed in a portion of the machine frame 2 and so disposed as to guide the raceway accurately without side play in its path toward and away from the setting die 10. The means for moving the raceway are not herein shown as they form no part of the present invention but may be of any desired construction.

The raceway is provided at a point above or remote from its delivery end with a spring stop 77 which serves to retain in the raceway a line of eyelets terminating short of its delivery end. A retaining member 76 provided with a recess for positioning the eyelet to be delivered is pivotally mounted upon the raceway and normally pressed into eyelet engaging position by a spring pin 78. The retaining member 76 is also provided with a projection 79 disposed oppositely to the end of the yielding stop 77 and so designed that when pressure is exerted upon the projection 79, as by an eyelet in moving past the stop 77, the retaining member will 110 be swung outwardly and the endmost eyelet released and left free to be engaged by the sectional spindle of the upsetting die 12.

The machine frame 2 is provided with a vertical guideway parallel to and at the rear of the plunger 4 in which is mounted a reciprocatory slide 42 carrying at its upper end a spindle 40 so located and shaped as to enter the barrel of that eyelet which is held in the raceway by the yielding stop 77. The slide 42 and its spindle are operated by a cam 50 formed on the periphery of the cam disk 54 through an arm 44 which engages a slotted stud on the slide 42 at its inner end and is fast at its outer end to a shaft 46 journaled in a bracket 60 secured to the machine frame. At its front end the shaft 46 is provided with a cam arm 48 having a roller to run upon the cam surface 50 and a spring which maintains engagement 130

with the cam. The cam 50 is so shaped that the spindle 40 is elevated when the raceway is moved forwardly to delivering position and is maintained in such position until the 5 raceway has been retracted to its rearmost position and the operation performed on the preceding eyelet.

It will be noted that the spindle 40 is solid in construction and of such diameter as 10 nearly to fill the barrel of the eyelet, being rounded at its upper end so as to center the eyelet in entering its barrel and sufficiently strong in construction to punch out and remove from the barrel any obstruction which 15 may be caused from enamel or a chip of eyelet metal within the eyelet barrel.

The punch lever 80 above referred to is provided with a punch 82 which coöperates with a punching die 84 arranged beneath 20 the punch in a slot in the work plate 70. The punching operation is effected by the downward movement of the punch 82 which is effected by swinging the lever 80 by a cam not herein shown. The lever 34 carries a feeding member 32 which includes a 25 yielding pin 30 cupped at its lower end for engagement with the die-expanding member 24, as shown in Fig. 9. The punching operation takes place at one side of the setting position whereupon the punch 80 is retracted from the work and moved to an inoperative position. The feed lever 34 is subsequently moved so as to carry the feeding pin 30 into alignment with the previously 30 punched hole, then depressed to engage the work and finally moved toward the left to bring the punched hole into alignment with the setting devices.

The setting devices and eyelet positioning 40 spindle are shown in their initial position in Fig. 4, the endmost eyelet in the raceway 72 having been drawn forward into the recess in the retaining member 76, as shown in Fig. 10, and the spindle 40 occupying its lower 45 position. When the machine is started the punching and feeding operations take place as above outlined and the plunger 4 is lowered while the raceway 72 is advanced to bring the endmost eyelet into line with the 50 sectional spindle of the upsetting die 12. The plunger 4 and the spindle 40 are then elevated as shown in Fig. 5, the upsetting die passing through the endmost eyelet and the spindle 40 passing into the barrel of the 55 eyelet held by the yielding stop 77. The raceway is then retracted as shown in Fig. 6, the eyelet engaged by the spindle 40 being held stationary and forced against the projection 79 of the retaining member 76 there- 60 by swinging the retaining member outwardly and freeing the endmost eyelet. The spindle 40 is then held at rest while the plunger 4 continues its upward movement to effect the clenching operation, as shown in 65 Fig. 6. The position of the parts at the

moment of clenching the eyelet is shown in Fig. 7. The plunger 4 and the spindle 40 are then both lowered to their initial positions and the eyelet which has previously been engaged by the spindle 40 is left in the 70 raceway engaged and positioned by the retaining member 76.

As herein shown the eyelet is inserted through the lining part of the upper only as is customary in setting invisible eyelets 75 and consequently the upward movement of the upsetting die member 12 is terminated by a stop 62 on the bracket 60 when it has passed through the lining part 90 of the upper as shown in Fig. 9. The feeding pin 80 30 is engaged by the die-expanding member 24 and forced upwardly out of the work but is then arrested in its movement so that in the continued elevation of the plunger 4 the sectional upsetting die 12 is forced upon the 85 conical surface of the member 24 and the die then expanded into upsetting condition. During this operation both the spring 20 and the spring 30 are compressed and as soon as the feeding lever is elevated the die-expanding member is returned to its initial 90 position and the upsetting die permitted to contract so that it may be drawn downwardly through the barrel of the clenched eyelet.

Having thus described my invention, what I claim as new and desire to secure by Letters Patent of the United States is:

1. A machine for setting fasteners, having, in combination, fastener-setting means, 100 a raceway for conducting fasteners thereto, and mechanism arranged to feed the fasteners one by one to said means, said mechanism being arranged to take complete hold of the second eyelet from the setting means and to 105 maintain such hold continuously until the fastener is taken under control by the setting means.

2. A machine for setting eyelets, having, 110 in combination, an eyelet-engaging device, a raceway for delivering eyelets to said device, and eyelet-feeding means constructed and arranged to enter the barrel of an eyelet in the raceway, other than the leading eyelet, said means and the raceway being relatively 115 movable, while said means occupies said barrel, to transfer the eyelet to delivering position relatively to the raceway.

3. A machine for setting eyelets, having, 120 in combination, a setting device, a raceway for supplying eyelets thereto, and a spindle movable to enter the barrel of an eyelet in the raceway at a point remote from the end of the raceway, said spindle and raceway being thereafter relatively movable to advance the eyelet to the end of the raceway.

4. A machine for setting eyelets, having, 125 in combination, a raceway for eyelets, a yielding stop arranged to arrest an eyelet in the raceway, means arranged to hold an eye-

- let between said stop and the delivery end of the raceway, and eyelet-feeding means including a spindle arranged and operated to enter the barrel of the eyelet restrained by 5 said stop, said spindle and the raceway being relatively movable while the spindle is in said barrel, to transfer the eyelet from said stop to said holding means.
5. A machine for setting eyelets, having, 10 in combination, a raceway for eyelets, a setting device including a spindle, a second spindle, and means for moving both spindles to enter separate eyelets in the raceway and then moving the spindles unequally.
- 15 6. A machine for setting eyelets, having, in combination, a frame having vertical and horizontal guideways formed therein, a movable raceway controlled in its path by one guideway, a spindle controlled in its 20 path by the other guideway, and means for moving the spindle to engage an eyelet in the raceway when the raceway occupies its rearmost position and to disengage the eyelet when the raceway is advanced.
- 25 7. A machine for setting eyelets, having, in combination, a setting device and spindle movable in parallel paths, and an eyelet raceway movable to position an eyelet first over the spindle and then over the setting 30 device.
- 35 8. A machine for setting fasteners, having, in combination, a movable raceway, a setting device, fastener engaging and positioning members movable successively to engage the same fastener at spaced points on the raceway, and means constructed and arranged to move the raceway when one of the fastener positioning members is in fastener engaging position thereby to position positively the fastener to be delivered to the setting device.
- 40 9. A machine for setting fasteners, having, in combination, a raceway, spaced fastener retaining devices arranged to restrain 45 separate fasteners against advancing in the raceway, and fastener engaging devices movable to engage and control, in turn, the same fastener as it is restrained successively by said retaining devices, said raceway and 50 one of said fastener engaging devices being relatively movable to transfer the fastener from one of said restraining devices to the other.
- 55 10. A machine for setting eyelets, having, in combination, a setting device including a sectional setting die, a raceway for supplying eyelets thereto, and a solid spindle for positioning an eyelet in the raceway preliminarily to its presentation by the race- 60 way in position for delivery.
- 65 11. A machine for setting eyelets, having, in combination, a setting device including a sectional setting die, a raceway having a retaining member for positioning an eyelet for delivery in the raceway, and a
- solid spindle for moving an eyelet to said retaining member prior to its delivery.
12. A machine for setting eyelets, having, in combination, a setting device, a raceway movable toward and from said device, said 70 setting device being movable to engage an eyelet in the raceway, means movable toward and from the raceway simultaneously with the setting device to engage another eyelet, and means for maintaining said first 75 mentioned means in engagement with its eyelet while the raceway is retracted from the setting device and while the latter is elevated to set the eyelet.
13. A machine for setting fasteners, having, 80 in combination, a raceway for fasteners, means for engaging a fastener in the raceway, and means for effecting a relative movement of the engaging means and the raceway in angularly related directions, said 85 raceway having means for holding a fastener in delivering position, and said means being constructed and arranged to release the fastener and leave it free at the time of its engagement by said removing means. 90
14. A machine for setting fasteners, having, in combination, a setting device, a raceway for supplying fasteners to said device, a retaining latch adjacent to the end of the raceway, and means for moving the latch 95 into inoperative position constructed and arranged to allow the fastener which is to be delivered to remain undisturbed by the operation of said latch moving means.
15. A machine for setting fasteners, having, 100 in combination, a setting device, a raceway for supplying fasteners to said device and having a movable retaining latch for positioning the endmost fastener, said latch being so constructed and arranged that 105 movement of another fastener in the raceway disengages the latch from the endmost fastener.
16. A machine for setting fasteners, having, 110 in combination, a setting device, a raceway for supplying fasteners thereto and having a movable retaining latch for positioning the endmost fastener, said latch being positioned for engagement by a succeeding fastener at a point remote from the endmost fastener to move the latch to release 115 said fastener when it is to be delivered from the raceway.
17. A machine for setting fasteners, having, 120 in combination, a setting device, a raceway for supplying fasteners thereto and having a pivoted retaining latch provided with a recess for positioning the endmost fastener and a projection, and means for swinging the latch out of engagement with 125 the endmost fastener, said projection and means being relatively movable.
18. A machine for setting fasteners, having, 130 in combination, fastener-setting means, a movable raceway for supplying fasteners

to be set by said means, a pivoted link arranged to guide a portion of said raceway, and other guiding means arranged to guide the raceway in a plane transverse to the pivotal axis of said link without affecting the curvilinear movement determined by said axis.

19. A machine for setting fasteners having, in combination, fastener-setting means, 10 a movable raceway for supplying fasteners to be set by said means, means arranged to restrict the movement of said raceway to lines parallel to one plane without restricting the movement in any direction parallel 15 to said plane, and a pivoted link arranged to guide the raceway in a definite path parallel to said plane, the pivotal axis of said link being at right angles to said plane.

20. A machine for setting eyelets, having, in combination, eyelet setting devices, a raceway for presenting eyelets thereto, and means for cleaning the barrel of each eyelet preliminarily to its presentation to the setting devices.

25 21. A machine for inserting annular fasteners having, in combination, a setting device, a raceway for supplying annular fasteners thereto, and movable means constructed and arranged to thread a fastener 30 in the raceway other than the endmost fastener at a point remote from the end of the raceway, said means and the raceway being thereafter relatively movable to advance the fastener to its ultimate dwelling position in 35 the raceway while said means remains in the fastener.

22. A machine for setting fasteners having, in combination, a setting device, a raceway for supplying fasteners thereto provided with a yielding stop remote from its 40 delivery end, and a retaining latch between said remote stop and said delivery end, and a feeding device constructed and arranged to transfer a fastener held by the yielding 45 stop from the latter to the retaining latch.

23. A machine for setting fasteners having, in combination, a setting device, a movable raceway for supplying fasteners to said setting device and constructed and arranged 50 for movement toward and away therefrom, and fastener engaging means movable toward and away from the raceway to engage a fastener therein, when the raceway occupies its retracted position and to disengage 55 the fastener when the raceway is in advanced position.

24. A machine for setting eyelets having, in combination, a raceway for the eyelets, means constructed and arranged to thread 60 an eyelet in the raceway and set it in the work, and independent means for positively positioning the eyelet in the raceway preliminarily to its presentation to said first

mentioned means in a position suitable for threading thereby.

25. A machine for setting fasteners, having, in combination, a fastener raceway, a setting device, a fastener engaging device, means for effecting a relative movement of the raceway and said devices to cause the 70 setting device to remove a fastener from the raceway and to cause said engaging device to advance another fastener in the raceway, and means for maintaining the latter device in control of the latter said fastener while 75 the first said fastener is being removed and set by the setting device.

26. A machine for setting fasteners having, in combination, a raceway for conducting a series of fasteners, fastener-setting means including an element arranged and operated to take the leading fastener from the raceway, means arranged to hold the leading fastener in a definite position for such taking, means arranged to restrain the 80 second fastener of said series at a position remote from the leading fastener, and means arranged to feed the second fastener from said restraining means to said holding means without relinquishing control of the 85 fastener during the transfer.

27. A machine for setting fasteners having, in combination, fastener-setting means, a raceway for conducting a series of fasteners to be set by said means, two fastener-restraining devices arranged to engage, respectively, the leading fastener and the second fastener of said series to maintain said fasteners a predetermined distance apart, and means arranged to feed the second fastener 100 from the first restraining device to the second restraining device, the latter being effective to take control of the fastener, with regard to forward and backward movement of the fastener, while such fastener is under the 105 control of said feeding means.

28. A machine for setting eyelets having, in combination, eyelet-setting means, a raceway for conducting a series of eyelets to be set by said means, two eyelet-restraining devices arranged to engage, respectively, the leading eyelet and the second eyelet of the series to maintain them a predetermined distance apart, and a spindle arranged to enter the barrel of the second eyelet to transfer 110 the latter from the first restraining device to the second restraining device in consequence of relative movement of said spindle and the raceway, said second restraining device being effective to take control of the 115 eyelet, with regard to both forward and backward movement, and means arranged to move the spindle into and out of the eyelet.

In testimony whereof I have signed my name to this specification.

PERLEY R. GLASS.
